UNITED STATES PATENT OFFICE.

JESSE D. LYON, OF CINCINNATI, OHIO, ASSIGNOR TO THE FULNAME COMPANY, OF CINCINNATI, OHIO, A CORPORATION OF OHIO.

GOLF-BALL MARKER.

1,204,578.

Specification of Letters Patent. Patented Nov. 14, 1916.

Application filed December 2, 1915. Serial No. 64,619.

To all whom it may concern:

Be it known that I, JESSE D. LYON, a citizen of the United States of America, and resident of Cincinnati, county of Hamilton, 5 State of Ohio, have invented certain new and useful Improvements in Golf-Ball Markers, of which the following is a specification.

This invention relates to improvements in 10 golf ball markers and particularly to golf ball markers of the type disclosed in my Patent 1,139,689 issued May 18, 1915.

The invention embodied herein consists in an improvement in the marking die and its 15 holder and has for an object to produce a marking die and holder in which improved means are employed for facilitating the insertion of dies in the holder. This and other objects are attained in the construction 20 described in the following specification and illustrated in the accompanying drawings, in which:

Figure 1 is an end elevation of a golf ball marking machine with one of the side 25 frame members broken away for convenience of illustration and having a die holder forming a detail of my invention with a die also forming a detail of my invention, mounted therein. Fig. 2 is a sectional view taken on 30 the line 2—2 of Fig. 1, with the die partially removed from the holder. Fig. 3 is a perspective view of the die shown mounted in Fig. 1.

The type of golf ball marker to which my 35 invention is particularly applicable and which is fully set forth in my above mentioned patent, consists of a base 4, a frame 5 pivotally mounted on the base, a holder or clamp 6 mounted at the pivot point of the 40 frame 5, adapted to hold the ball with its axis in alinement with the pivotal point of the frame, and operated by a handle 7, a die holder 8 pivotally mounted by means of a ball and socket joint 9, and means 10 for 45 moving the pivotal point 9 of the die holder 8, to and from the ball holder 6. The means for operating the ball clamp need not be more fully described since it forms no portion 50 of the present invention. The die holder is provided with a curved portion 11 having a curved recess 12 formed therein, the curvature thereof being on a circle 55 drawn about the pivot point 9. The flanges on each side of the curved recess 12 are preferably of unequal depth, one curved

flange 13 being somewhat deeper than the opposite curved flange 14. The curved die 15 which is adapted to be mounted in the holder, is provided with a curved tongue 16 for occupying the recess 12, and a relatively 60 thick curved flange 17 adapted to rest upon the edge of the flange 14, on one side of the die, with a thinner curved flange 18 formed on the opposite side of the die and adapted to rest upon the deep flange 13 of the 65 holder. The holder-engaging surfaces of the flanges 17 and 18 abut the edges of the flanges 13 and 14 when the tongue 16 occupies the recess 12, thus causing the inner faces 19 and 20 of the flanges 17 and 18 to 70 occupy different planes with relation to one another. The outer faces 21 and 22 of the flanges 17 and 18, forming the surface 23 of the die upon which the type 24 is formed, are part of one cylindrical surface and form 75 a supporting surface which engages the surface of the ball when the type is embedded in the material of the ball at the time the operating means 10 is caused to move the die holder 8 toward the ball. The flanges 17 80 and 18 extend the entire width of the holder 11 and thus afford ample support for the die and hold it securely in position. A stop 25 is located in the recess 12 for the purpose of forming an abutment against which 85 the die rests when it is placed within the holder.

The die is to be placed in the holder of the marker when the frame 5 has been 90 moved to occupy the position fragmentally shown in dotted lines in Fig. 1, and in mounting the die it is preferably placed in the holder by moving it transversely of the portion 11 from the side of the flange 14 toward the deeper flange 13, so that the 95 tongue 16 will move across the top of the flange 14 and abut the inner face of the flange 13 so as to prevent the tongue moving beyond the recess 12, thus assuring the proper positioning of the die. This construction is to overcome the objection to having to place the end of the die in engagement with the end of the holder and then of having to move the die through the 100 holder until it abuts the stop 25, an operation which requires an expenditure of care and time. Were the flanges of equal height the die 15 could not be placed in position as readily as in my improved construction, 105 since the die would have to be as carefully 110

centered in the recess before bringing it to its final position, as though it were to be moved from the end of the holder to its final position, as previously described. In 5 my improved construction I have therefore provided a simple but effective means of quickly centering and positioning the die in the holder with the least possible expenditure of care and time in the mounting operation. This is particularly desirable since the golf player has a die adapted to print his name and the same marker is provided for all the club members. The player being usually in a hurry to mark the balls and get 10 into his game may, with my improved construction, properly insert the die in its holder without exercising either care or skill in so doing.

Having thus described my invention, 20 what I claim is:

1. In combination in a marking machine, a die holder, and a die adapted to occupy the die holder, said holder having a centrally located recess, a shallow flange forming one side of the recess and a deep flange 25 forming the opposite side of the recess, said die having a projection adapted to occupy the recess, a thick flange adapted to engage the shallow flange of the holder, and 30 a thin flange adapted to engage the deep flange of the holder, the outer surface of the die having type formed thereon for marking the ball.

2. A golf ball marker comprising, a ball 35 holder, and a rocking die holder coöperating therewith and adapted to rock a die over the surface of a ball located in the holder, said holder having a centrally located recess, flanges of unequal height at 40 the sides of the recess, and a die adapted to occupy the holder, said die having a projection adapted to occupy the recess and flanges of unequal thickness for engaging the flanges of the holder, whereby the die

may be placed in the holder in but one position to properly present it to the surface of a ball located in the holder. 45

3. In a golf ball marking machine, a ball clamp, a die holder coöperating with the clamp, and a die located in the holder, said 50 holder being adapted to rock the die over a ball located in the clamp and having a recess centrally located therein, with a narrow flange forming one side of the recess and a deeper flange forming the opposite side of 55 the recess, said die having a tongue adapted to occupy the recess, a thick flange adapted to engage the top of the narrow flange, and a thin flange adapted to engage the top of the deep flange, the outer surfaces of the 60 flanges being part of the same cylindrical surface and forming the ball engaging surface of the die, upon which the marking type is located.

4. In combination in a golf ball marker, 65 a ball clamp, and a curved rocking die holder coöperating therewith and adapted to rock a die over the surface of a ball located in the clamp, said holder having a centrally located curved recess, curved 70 flanges of unequal height at the sides of the recess, and a curved die adapted to occupy the holder, said die having a curved tongue adapted to occupy the curved recess, and curved flanges of unequal thickness for engaging the curved flanges of the holder, 75 whereby the curved die may be placed in the curved holder in but one position to properly present it to the surface of a ball located in the clamp.

In testimony whereof, I have hereunto subscribed my name this 30th day of November, 1915.

JESSE D. LYON.
